ELECTRICAL CONNECTION BOX

John Elwood Dieffenderfer, Constantine, Mich.,
assignor of one-half to J. Mark Harvey, Dear-
born, Mich.

Application February 4, 1946, Serial No. 645,440

10 Claims. (Cl. 220—3.6)

1

The main objects of this invention are:

First, to provide an outlet or switch box or the like which may be quickly and securely mounted in a wall opening, the inner retaining means being engaged from the front of the box.

Second, to provide a connection box having means for securing it to a support manipulated entirely from the front of the box, and at the same time one which is effective in anchoring the box to the support.

Third, to provide a structure having these advantages which is simple and economical in its parts in assembly thereof and in manipulation.

Objects relating to details and economies of the invention will appear from the description to follow. The invention is defined and pointed out in the claims.

A structure which embodies the features of the invention is illustrated in the accompanying drawing, in which:

Fig. 1 is a front elevation of an outlet box embodying my invention in assembled relation to a wall panel.

Fig. 2 is a fragmentary view in section on line 2—2 in Fig. 1, one of the bracket members being shown in engaged position by full lines, the other being shown in initial position by full lines and in engaged position by dotted lines.

Fig. 3 is a fragmentary rear perspective view.

Fig. 4 is a perspective view of one of the mounting brackets.

In the accompanying drawing, 1 represents a wall panel of plaster, beaver board, or the like having a hole 2 therein adapted to receive the connection box 3, an outlet box being illustrated.

In this preferred embodiment I provide a pair of bracket members designated generally by the numeral 4, these being mounted on the outer sides of opposed walls of the box. Bracket members 4 are formed of sheet metal folded to provide an outwardly projecting flange 5 adapted to overlap the front side of the support. The forming of the flange by folding the stock provides the desired rigidity with relatively light stock or stock of light gage.

The brackets are in effect angular in shape and have slots 6 adapted to receive the attaching screws 7. The brackets have inwardly projecting bendable arms 8, the arms desirably having spaced weakened zones 9 resulting from holes 10. Straps 11 preferably integral with the arms are reversely folded thereon and of such length as to project initially upon the front of the box as shown in Fig. 2, so that they may be grasped with pliers or other suitable tool and a pull ex-

2

erted thereon would result in the bending of the arms at the weakened zones into engagement with the inner sides of the support as shown at 12 in the drawings, that is, the arms are bent outwardly to project behind the edges of the support openings and to engage the support in opposed relation to the flanges 5 of the brackets.

After the retaining arms have been bent into engaging position, the ends of the straps are folded over the edges of the box and disposed within the box as shown at 13. This enables the very rigid anchoring of the box in the support opening. Should it become necessary to renew the box, the ends of the strap may be swung to extended position and a tool inserted to bend the arms back against the sides of the box or out of engagement with the support, permitting the box to be renewed.

My improved brackets may be very economically produced and they are very quickly and easily manipulated for the mounting of the box.

I have not attempted to illustrate or describe various adaptations or modifications which may be desirable for particular designs or types of boxes, as it is believed that these disclosures will enable those skilled in the art to embody or adapt my invention as may be desired.

Having thus described my invention, what I claim as new and desire to secure by letters 30 patent is:

1. The combination with a connection box, of brackets mounted on the outer sides of opposed walls of the box and having laterally projecting support engaging flanges, said brackets having transversely spaced inwardly projecting bendable arms disposed along the sides of the box and having longitudinally spaced weakened zones, and straps integral with and extending from the inner ends of the arm and reversely folded relative thereto to lie between said arms and the sides of the box and initially projecting beyond the front edges of the arms whereby they may be grasped and the arms bent outwardly relative to the box into retaining clamping engagement with a support in opposed relation to the flanges of the brackets by pulling on the straps and the straps then folded over the edges of the box into retaining engagement therewith with the ends of the straps disposed within the box.

2. The combination with a connection box, of brackets mounted on the outer sides of opposed walls of the box and having laterally projecting support engaging flanges, said brackets having transversely spaced inwardly project-

ing bendable arms disposed along the sides of the box and having longitudinally spaced weakened zones, and straps integral with and extending from the inner ends of the arms and reversely folded relative thereto and initially projecting beyond the front edges of the arms whereby they may be grasped and the arms bent outwardly relative to the box into retaining clamping engagement with a support in opposed relation to the flanges of the brackets by pulling on the straps.

3. The combination with a connection box, of brackets mounted on the outer sides of opposed walls of the box and having laterally projecting support engaging flanges, said brackets having inwardly projecting bendable arms disposed at the sides of the box, and bendable straps integrally connected to the inner ends of the arms and of a length substantially greater than that of the arms to initially project outwardly beyond said support engaging flanges whereby they may be grasped and the arms bent outwardly relative to the box into retaining clamping engagement with a support in opposed relation to the flanges of the brackets by pulling on the straps, the ends of said straps being folded over the edges of the box into retaining engagement therewith with the ends of the straps within the box.

4. The combination with a connection box, of brackets mounted on the outer sides of opposed walls of the box and having laterally projecting support engaging flanges, said brackets having inwardly projecting bendable arms disposed at the sides of the box and bendable straps integrally connected to the inner ends of the arms and of a length substantially greater than that of the arms to initially project outwardly beyond said support engaging flanges whereby they may be grasped and the arms bent outwardly relative to the box into retaining clamping engagement with a support in opposed relation to the flanges of the brackets by pulling on the straps.

5. A bracket adapted to be mounted in pairs on opposite sides of a connection box and having a laterally projecting support engaging flange arranged to be clamped against the front surface of a support alongside of an opening in the support in which the box is received, said bracket having rearwardly projecting transversely spaced bendable arms disposed in parallel relationship along the side of the box and having longitudinally spaced weakened portions, and straps integrally connected with and extending from the rear ends of said arms and reversely folded relative thereto and initially projecting beyond the front edge of the arms whereby the straps may be grasped and pulled forwardly relative to the box causing the arms to bend at said weakened portions and swing the rear portions of said arms outwardly relative to the box into retaining engagement with the rear edge of the opening in said support.

6. A bracket adapted to be mounted in pairs on opposite sides of a connection box and having a laterally projecting support engaging flange arranged to be clamped against the front surface of a support alongside of an opening in the support in which the box is received, said bracket having a rearwardly projecting bendable arm disposed in parallel relationship along the side of the box and having longitudinally spaced weakened portions, and a bendable strap integrally

connected with and extending from the rear end of said arm and reversely folded relative thereto and of a length greater than that of said arm to initially project beyond the front edge of the arm whereby the strap may be grasped and pulled forwardly relative to the box causing the arm to bend at said weakened portions and swing the rear portion of said arm outwardly relative to the box into retaining engagement with the rear edge of the opening in said support.

7. A support engaging bracket adapted to be secured to the side wall of a connection box comprising, a flange on said bracket projecting laterally from the front edge of said box when 15 said bracket is mounted thereon, a rearwardly projecting bendable arm on said bracket, and a strap integrally connected to the rear end of the arm and reversely folded and disposed initially in lapped relationship between said arm and said 20 side with the free end of the strap projecting forwardly beyond the front edge of the box whereby the rear portion of the arm may be bent outwardly of the box into retaining engagement with a support by pulling forwardly on 25 the strap.

8. A support engaging bracket adapted to be secured to the side wall of a connection box comprising, a flange on said bracket projecting laterally from the front edge of said box when 30 said bracket is mounted thereon, a rearwardly projecting bendable arm on said bracket, and a strap connected to the rear end of the arm and of a length greater than that of said arm to initially project forwardly beyond the front edge 35 of the box whereby the rear portion of the bracket may be bent outwardly of the box into retaining engagement with a support by pulling forwardly on the strap, the free end of said arm being bendable back upon itself to constitute 40 securing means for the same.

9. A bracket for mounting a connection box comprising, an arm adapted to be secured to and disposed along the side of the box and having a bendable rear portion, and a bendable strap 45 connected to the rear portion of the arm and of a length greater than that of said arm to initially project forwardly beyond the edge of the box whereby the arm may be bent outwardly relative to the box into retaining engagement 50 with a support by a pull on the strap and the strap then folded over an edge of the box.

10. A bracket for mounting a connection box comprising, an arm adapted to be secured to and disposed along the side of the box and having 55 a bendable rear portion, and a bendable strap integrally connected to the rear portion of the arm and of a length greater than that of said arm to initially project forwardly beyond the edge of the box whereby the arm may be bent outwardly relative to the box into retaining engagement with a support by a pull on the strap.
